J. B. DAUDELIN

SHUTTLE

Filed April 13, 1923

Inventor
Jean B. Daudelin
By *Elie Spaeth*,
Attorney

UNITED STATES PATENT OFFICE.

JEAN B. DAUDELIN, OF FALL RIVER, MASSACHUSETTS.

SHUTTLE.

Application filed April 13, 1923. Serial No. 631,918.

To all whom it may concern:

Be it known that I, JEAN B. DAUDELIN, a citizen of the United States, residing at Fall River, county of Bristol, Commonwealth of Massachusetts, have invented certain new and useful Improvements in Shuttles, of which the following is a specification.

This invention relates to automatically threading shuttles for use in weft replenishing looms, and involves certain improvements over the shuttle described and claimed in my prior application, Serial No. 530,190, filed January 18, 1922, to which reference is made as illustrating the type of shuttle involved herein.

My present invention is particularly directed to the construction of the threadder itself, to the end that the shuttle may be quickly and conveniently threaded and that when threaded the weft will be prevented from improper escape from the threading eye during the run of the shuttle, and consists in the novel construction, combination, and relation of parts described and illustrated in the accompanying specification and drawings and particularly pointed out in the appended claims. Throughout the specification and drawings like reference characters are correspondingly applied, and in the drawings:

Fig. 1 is a partial plan view at the threading end of an automatic loom shuttle of standard type equipped with a threadder in accordance with my invention.

Fig. 2 is a side elevation thereof.

Figs. 3 and 4 are side elevations of the threadder removed and viewed from the delivery and intake ends, respectively, of the threading eye, and

Figs. 5 and 6 are end elevations as viewed from the right and left, respectively, of Fig. 3.

I have indicated at 1 a portion of a loom shuttle of standard type, at 2 the shuttle throat, at 3 the threading eye and at 4 the weft carrier. My threadder is indicated generally at T and is mounted in approximately the longitudinal axis of the shuttle throat. As here shown the threadder is a metallic casting comprising a top wall 5, a depending vertical side wall 6, a bottom wall 7 and an upturned vertical extension 8 defining with said walls 5, 6 and 7 an open-ended recess within which is mounted a

thread guide 9. The bottom wall 7 has a depending stud 10 adapted to fit within a hole formed in the bottom of the shuttle throat and the vertical extension 8 thereof is shouldered at one end as indicated at 12 60 to fit within a vertical groove in the shuttle body and key the threadder in the shuttle throat.

The guide 9 is preferably a helical coil seated in the open-ended recess of the 65 threadder and at its rear end abutting a narrow shoulder 10' formed on the under face of the top wall 5 of the threadder. This shoulder prevents the weft W from lifting out of the coil during the run of the shuttle. 70 Beyond the shoulder 10' the top wall 5 of the threadder extends as a downturned guide tongue 11 effective in threading to direct the weft from the weft carrier downwardly into the guide coil. 75

One end of the coil is bent substantially vertically downwardly as indicated at 9', Figs. 4 and 5, to overlie the upturned wall 8 of the threadder, the rear edge of said extension 9' abutting the shoulder 12 of said 80 wall. The extensions 8 and 9' and wall 6 are pierced by a hole 13 for the reception of the anchoring screw 14, Fig. 2, which passes transversely of the shuttle throat from side to side thereof and fixes the 85 threadder within said throat.

Beyond the forward end of the guide coil, the top wall of the threadder is provided with a depending vertical snubbing post 15 disposed substantially in line with the 90 axis of the guide coil. Forwardly of said guide post 15 and offset laterally with respect thereto, is a downwardly and rearwardly tapering guide pin 16 formed integrally with the top wall of the threadder 95 and terminating short of the lower end of the snubbing post 15. The wall 6 of the threadder is notched, as indicated at 17, Fig. 3, to permit the weft to pass laterally from the guide pin 16 into the intake end of the 100 threading eye. Extending laterally over the threading eye from the top wall of the threadder, is a downwardly and rearwardly disposed tongue 18 from which depends a vertical rib 19. The rib 19 is parallel to 105 the longitudinal axis of the threading eye and slightly in advance thereof. There is a clearance between the forward edge of the tongue 18 and the wood of the shuttle at this side of the shuttle eye, such clearance con- 110

stituting an inlet port 18' by means of which the weft, in threading, may enter the eye 3 from above, the rib 19 terminating short of the overlying tip of the tongue 18, as indicated at 19', Figs. 5 and 6, to permit the weft to clear said rib in entering the eye. The extreme forward end of the threader at the side opposite the tongue 18 is formed with a down-turned guide tongue 20.

10 The threading eye 3 is provided with a vertical inlet slot 21 opening into said eye from above and connecting with the port 18', and at its delivery end, a pair of guide pins is set through the wood of the shuttle 15 on either side of said eye. These pins define the delivery end of the eye. The intake end of the eye is defined by the metal of the threader on either side of the notch 17, the snubbing post 15 being disposed substantially in the longitudinal axis of the eye in rear of said notch.

In threading the shuttle, the weft from the weft carrier 4 is drawn into the space between the outermost turn of the helical 25 guide coil and the anchoring portion 9' thereof, the guide coil being preferably wound in a direction opposite to the unspooling action of the weft so that the weft will automatically work its way towards the 30 center of the coil. From the coil the weft passes over the snubbing post 15 and down the guide pin 16 into the port 18' along the forward side of the rib 19 and into the inlet slot 21 of the eye. The shuttle is now 35 threaded and the weft runs from the coil directly past the snubbing post 15 and through the notch 17 into the eye. Any tendency of the weft to escape by direct, upward lifting movement is met by the rib 19, which thus 40 prevents the weft from drawing backwardly along the tongue 18 into the port 18'. The weft is therefore compelled to pass outwardly between the guide pins 22.

Various modifications in the form and 45 construction of my device may obviously be resorted to without departing from the spirit of my invention if within the limits of the appended claims.

What I therefore claim and desire to secure by Letters Patent is:—

1. In a shuttle having a threading eye, a threader mounted longitudinally of the shuttle throat, a tongue overlying the threading eye and defining with the adjacent portion of the shuttle body a thread inlet port opening into said eye from above and a vertical rib depending from said tongue and extending above and parallel to the longitudinal axis of said eye and constituting a barrier effective to prevent escape of the weft from said eye by an upward lifting movement.

2. In a shuttle having a threading eye, a threader mounted longitudinally of the shuttle throat, a tongue overlying the

threading eye and defining with the adjacent portion of the shuttle body a thread inlet port opening into said eye from above, and a rib depending from said tongue and extending above and parallel to said eye and in slightly offset relation to the longitudinal axis of said eye and constituting a barrier effective to prevent escape of the weft from said eye by a direct upward lifting movement, said rib terminating short of the tip of said tongue to permit the weft, in threading the shuttle, to pass from the inlet port directly into the eye.

3. In a shuttle having a threading eye, a threader mounted longitudinally of the shuttle throat and having a notch defining the intake end of the threading eye, a tongue overlying said notch and defining with the adjacent portion of the shuttle body a thread inlet port opening into said eye from above, and a rib depending from said tongue and extending above and parallel to the threading eye in slightly offset relation to the longitudinal axis thereof and constituting a barrier effective to prevent escape of the weft from said eye by an upward lifting movement.

4. In a shuttle having a threading eye, a threader having a notch defining the intake end of the threading eye, a tongue overlying said notch and defining with the adjacent portion of the shuttle body, a thread inlet port opening into said eye from above, and a rib depending from said tongue and extending above and parallel to the threading eye in slightly offset relation to the longitudinal axis thereof and constituting a barrier effective to prevent escape of the weft from said eye by an upward lifting movement, said rib terminating short of the tip of said tongue to permit the weft, in threading the shuttle, to pass from the inlet port directly into the eye.

5. A shuttle having a threading eye, a threader having a weft guide disposed longitudinally of the shuttle throat, a snubbing post disposed in advance of said guide, said threader having a notch in line with said snubbing post and defining the intake end of the threading eye, a tongue overlying the threading eye and defining with the adjacent portion of the shuttle body a thread inlet port opening into said eye from above, and a rib depending from said tongue and extending above and parallel to the threading eye in slightly offset relation to the longitudinal axis of said eye and constituting a barrier effective to prevent escape of the weft from said eye by an upward lifting movement.

6. In a shuttle having a threading eye, a threader having a weft guide disposed longitudinally of the shuttle throat, a snubbing post disposed in advance of said guide, a guide pin disposed in advance of said snub-

- bing post and slightly offset laterally relative thereto, said threader having a notch in line with said snubbing post and defining the intake end of the threading eye, a tongue 5 overlying the threading eye and defining with the adjacent portion of the shuttle body a thread inlet port opening into said eye from above, and a rib depending from said tongue and extending above and parallel 10 to the threading eye in slightly offset relation to the longitudinal axis of said eye and constituting a barrier effective to prevent escape of the weft from said eye by an upward lifting movement.
- 15 7. In a shuttle having a threading eye, a threader mounted longitudinally of the shuttle throat and comprising a top wall, a vertical side wall, a horizontal bottom wall and a vertical extension of said bottom wall, 20 said walls defining an open-ended recess and said extension shouldered at its rear end to constitute a key effective to frictionally retain the threader within the shuttle throat, and a guide coil mounted within said recess and at its rear end abutting said shoulder.
- 25 8. In a shuttle having a threading eye, a threader mounted longitudinally of the shuttle throat and comprising a top wall, a vertical side wall, a horizontal bottom wall, 30 and a vertical extension of said bottom wall, said walls defining an open-ended recess, a guide coil mounted within said recess, the upper wall of said threader having a depending rib disposed transversely of said 35 guide coil and effective to prevent the weft lifting out of said coil during the run of the shuttle.
9. In a shuttle having a threading eye, a threader mounted longitudinally of the 40 shuttle throat and comprising a top wall, a vertical side wall, a horizontal bottom
- wall and a vertical extension of said bottom wall, said walls defining an open-ended recess, and said extension shouldered at its rear end to constitute a key effective to frictionally retain the threader with the shuttle throat, and a guide coil mounted within said recess and at its rear end abutting said shoulder, the upper wall of said threader having a depending rib disposed transversely of said guide coil and effective to prevent the weft lifting out of said coil during the run of the shuttle. 45
10. In a shuttle having a threading eye, a threader mounted longitudinally of the shuttle throat and comprising a top wall, a vertical side wall, a horizontal bottom wall and a vertical extension of said bottom wall, said walls defining an open-ended recess, a guide coil mounted within said recess, a snubbing post in advance of the guide coil, a guide pin depending from the top wall of the threader in advance of the snubbing post and laterally offset relative thereto, there being a space between said guide pin and the forward edge of the vertical side wall of the threader and said space defining the intake end of the threading eye, a downwardly and rearwardly disposed tongue extending from the top wall 50 of the threader and overlying said space, and a rib depending from said tongue and terminating short of the tip thereof and constituting a barrier effective to prevent escape of the weft from the threading eye 55 by a direct upward lifting movement. 70
- 75 In testimony whereof I affix my signature in presence of two witnesses.
